UNITED STATES PATENT OFFICE.

EDWIN E. BARNEY, OF GROTON, NEW YORK, ASSIGNOR, BY DIRECT AND MESNE ASSIGNMENTS, TO UNION TYPEWRITER COMPANY, A CORPORATION OF NEW JERSEY.

TYPE-WRITING MACHINE.

No. 833,112.

Specification of Letters Patent.

Patented Oct. 9, 1906.

Original application filed June 11, 1900, Serial No. 19,889. Divided and this application filed January 27, 1902. Serial No. 91,465.

To all whom it may concern:

Be it known that I, EDWIN E. BARNEY, of Groton, in the county of Tompkins, in the State of New York, have invented new and useful Improvements in Type-Writing Machines, of which the following, taken in connection with the accompanying drawings, is a full, clear, and exact description.

This case is a division of my application filed June 11, 1900, Serial No. 19,889.

This invention relates to improvements in type-writing machines, and refers more particularly to the type-bar and its hanger or support.

One of the objects of this invention is to simplify the construction of this part of the machine and to permit the use of a greater number of type in the same or less space than has heretofore been customary.

Another object is to enable any ordinary or unskilled workman to easily and quickly assemble these elements in the machine in perfect alinement without further adjustment, thereby materially reducing the cost of the machine.

A further object is to provide a substantially indestructible bearing for the type-bar, by which said type-bar is held in permanent alinement, its action is rendered easier and more responsive to the touch of the key, and the stroke upon the platen is more effective.

To these and other ends, which will hereinafter appear, the invention consists in the combination, construction, and arrangement of the parts of a type-bar and its hanger, as hereinafter fully described, and pointed out in the claims.

Referring to the drawings, Figure 1 is a side elevation of my improved hanger and type-bar mounted thereon with the segment in section and showing a platen and a key for operating the type-bar. Figs. 2, 3, and 4 are respectively front, rear, and side elevations of my invention, a portion of the type-bar being broken away in Fig. 4 to show more clearly the supporting-fin. Fig. 5 is a sectional view on line 5-5, Fig. 4. Figs. 6 and 7 are isometric views, respectively, of the hanger and washer-bearing, the latter part being considerably enlarged. Fig. 8 is a plan of a portion of the segment having the hanger-receiving slots and one of the hangers

as mounted therein and held by a suitable screw.

Similar reference characters indicate corresponding parts in all the views.

This invention consists, essentially, of a hanger and a type-bar pivotally mounted thereon, the hanger being composed of a body portion 1, having a guiding-fin 1^a, which is preferably segmental in form, a bearing or sleeve 2, and a fastening member, such as a rivet or bolt 3, and the type-bar consists of an oscillatory arm 4 and a type-plate 5 secured thereto.

Each hanger is preferably formed of thin sheet metal having an arm 6 and an aperture 7, the arm 6 being adapted to be inserted and to receive a radial adjustment in one of a series of slots 8 of a segment, quadrant, or frame 9 and held therein by any suitable means—such, for instance, as a screw 8'. Each of the hangers being substantially flat or plate-like and being formed of thin sheet metal, it is apparent that the slots in the frame 9 may be arranged very closely together side by side in the form of an arc, so as to permit a large number of hangers to be mounted in a short arc and to cause the type-bars to travel closely together without interference and to print at a common point upon the platen. The aperture 7 in the hanger is of sufficient diameter to form a substantial bearing for the sleeve 2, presently described, and its walls are usually hardened to prevent undue wear and to thereby insure a more perfect alinement of the type-bar when in action.

The guiding-fin 1^a preferably extends a considerable distance at either side of the aperture 7, and being of substantially the same, or slightly less thickness than the distance between the side walls of the type-bar it forms additional support to prevent any possible lateral displacement of said type-bar.

The arms 6 of the hangers are usually of less depth than the depth of the slots 8 and are so arranged as to fit closely in the slots with their upper edges within or beneath the upper surface of the segment.

The sleeve 2 preferably consists of a small metal washer of substantially the same diameter as the aperture 7, is inserted in said aperture, and is adapted to fit closely between

the side walls of the type-bar formed at the bifurcated heel thereof, being just enough thicker than the thickness of the hanger and guiding-fin to prevent the side walls of the type-bar from binding against the sides of the hanger and guiding-fin and still fitting sufficiently close to hold the type-bar in perfect alinement when in action. The peripheral surface of this sleeve is usually hardened 5 to receive the hardened bearing-surface of the hanger, said sleeve being impinged between the side walls of the type-bar and forms a substantially integral part of the type-bar to rock therewith. A suitable aperture 10 is formed centrally through the sleeve 2 to receive the rivet or bolt 3, which passes through apertures in the side walls of the type-bar and is riveted thereto.

The type-bar 4 is also preferably formed of sheet metal and is usually cut to the desired blank form and then folded, so as to be substantially U-shaped in cross-section, the front side of the lower portion being open, and the upper ends of the side walls are generally 20 pressed together and bent rearwardly a short distance to receive the type-plate 5. The lower end of the rear wall, as 11, of the type-bar is cut away at 12 to form the bifurcation in which the hanger and guiding-fin are received, and the adjacent inner faces of the side walls, as 13, are separated a distance substantially equal to the thickness of the hanger and guiding-fin or just clearance enough to permit the free action of the type-bar without permitting any lateral movement which would throw the type out of 30 proper alinement.

The type-plate 5 may be of any desired form or provided with any number or character of type and is preferably provided with a recess 14 to receive the rearwardly-projecting offset in the upper end of the type-bar. These parts may then be soldered or may be secured together in any other manner desired.

The operation of the construction will now be readily understood upon reference to the foregoing description and the accompanying drawings, and it will be noted that some 40 changes may be made in the detail construction and arrangement of the parts without departing from the spirit of the invention.

Having thus described my invention, what I claim, and desire to secure by Letters Patent, is—

1. In a type-writing machine, the combination with a hanger having a circular opening, a cylindrical member journaled in the opening, and a type-bar having portions 50 thereof extended on opposite sides of the hanger and secured to the opposite ends of the cylindrical members.

2. In a type-writing machine, the combination with a type-bar having separated 60 walls, a hanger having a portion thereof in-

serted between the walls and of slightly less thickness than the distance between said walls, said portion of the hanger having a circular opening, a cylindrical member inserted in the opening and having its opposite 70 ends secured to the side walls of the type-bar.

3. In a type-writing machine, the combination with a type-bar and a hanger, both having alined openings, the type-bar having separated walls and the hanger being inserted 75 between the walls, a cylindrical member inserted in the opening in the hanger and having its opposite ends abutting against the inner faces of the walls of the type-bar, the member being of slightly-greater length than 80 the thickness of the hanger, and means for securing the type-bar to said member.. .

4. In a type-writing machine, the combination of a supporting-hanger having a circular aperture, a type bar having separated 85 walls arranged on opposite sides of the hanger, said walls being separated a slightly-greater distance than the thickness of the hanger and provided with an aperture alined with the aperture of the hanger, a sleeve in 90 the aperture of the hanger and impinged between the side walls of the type-bar, and a fastening member passed through the apertures and sleeve.

5. In a type-writing machine, a type-bar 95 joint comprising a hanger, a metal ring of substantially the same thickness as the hanger and having a working fit therein, a type-bar having portions embracing said hanger and ring, and means connecting said 100 type-bar rigidly to said ring.

6. In a type-writing machine, the combination of a type-bar and hanger, one of said parts being bifurcated to receive the other, a bushing seated in the inserted member, and 105 a pivot-pin that extends through both sides of said bifurcated portion and through the bushing.

7. In a type-writing machine, the combination of a type-bar and hanger, one of said parts being bifurcated to receive the other, a bushing loosely seated in the inserted member, a pivot-pin that extends through both sides of said bifurcated portion and through 115 the bushing, and means for securing said pivot-pin to the bifurcated portion.

8. In a type-writing machine, the combination of a bifurcated type-bar, a hanger received in the bifurcated portion of said type-bar and having a bearing-opening therein, 120 and a cylindrical bearing-sleeve received within the bearing-opening in the type-bar and connected to the type-bar to turn there-with.

9. In a type-writing machine, the combination of a bifurcated type-bar, a hanger received between the arms formed by the bifurcated portion of said type-bar and having a bearing-opening therein, and a cylindrical bearing-sleeve received within the bearing- 125 130

- opening in the type-bar and riveted to the type-bar to turn therewith.
10. In a type-writing machine, the combination of a bifurcated type-bar, a hanger received in the bifurcated portion of said type-bar and having a bearing-opening therein, the bearing-walls of said opening being hardened, and a hardened sleeve received within the bearing-opening in the type-bar and connected to the type-bar to turn therewith.
11. In a type-writing machine, the combination of a bifurcated type-bar, a hanger received between the arms formed by the bifurcated portion of said type-bar and having a bearing-opening therein, the bearing-walls of said opening being hardened, and a hardened sleeve received within the bearing-opening in the type-bar and riveted to the type-bar to turn therewith.
12. In a type-writing machine, the combination of a type-bar and a hanger, one of said members being bifurcated to receive the other member between the arms formed by the bifurcated portion, and the other member having a bearing-opening extending therethrough, a bearing-sleeve received with-
- in said bearing-opening and riveted to the bifurcated portion.
13. In a type-writing machine, the combination of a type-bar and hanger, one of said members being bifurcated to receive the other member between the arms formed by the bifurcated portion, and the other member having a bearing-opening extending therethrough and the bearing-walls of which are hardened, a cylindrical hardened bearing-sleeve received within said bearing-opening and riveted to the bifurcated portion.
14. In a type-writing machine, the combination of a type-bar having a bifurcated portion, a hanger having a plate-like segmental fin that is received in the bifurcated portion of the type-bar to guide the latter in its printing movement, and a detachable bearing-sleeve received in a bearing-opening in the hanger and secured to the type-bar.

In witness whereof I have hereunto set my hand this 18th day of January, 1902.

EDWIN E. BARNEY.
